UNITED STATES PATENT OFFICE.

GEORGE B. FESSENDEN, OF BOSTON, MASSACHUSETTS, ASSIGNOR TO THE ECO MAGNETO CLOCK CO., OF BOSTON, MASSACHUSETTS, A CORPORATION OF MAINE.

ELECTRIC WATCHMAN'S CLOCK.

974,561.

Specification of Letters Patent. Patented Nov. 1, 1910.

Application filed July 23, 1908. Serial No. 444,897.

To all whom it may concern:

Be it known that I, GEORGE B. FESSENDEN, a citizen of the United States, and a resident of Boston, county of Suffolk, Commonwealth of Massachusetts, have invented 5 certain new and useful Improvements in Electric Watchmen's Clocks, of which the following is a specification.

This invention relates to electric watch- 10 man's clocks and more particularly to that class known as the "barrel" or "cylindrical" dial type.

The object of the invention is to provide 15 improved means for permitting the movement of a cylinder in a clock in which the dial is used more than for one night, namely, for instance, for three nights, or, if so desired, for one week.

In one day dial clocks it is necessary to 20 replace the dial every day, which becomes especially objectionable Saturdays and Sundays, as it requires a special errand to the works of the superintendent for the purpose of substituting the dials. In those 25 clocks which are used for more than one day, a dial is provided which has the divisions heretofore used, subdivided so as to conform to more than one cycle of operations and in order to use said dial means for 30 bringing said dial in position so as to be properly marked by the marking devices are required.

The nature of this invention consists in 35 means for bringing about the movement of the cylinder with the dial, consisting of a spring-actuated release device having flanges of different heights, and having projections to be engaged so as to rotate the device and bring about the shifting of the flanges, 40 so as to change their position relatively to the cylinder.

The invention consists also in the combination of a cylinder tending to move in one direction and automatic means adapted to 45 be moved positively so as to allow the cylinder to shift in said first named direction at the end of each complete rotation of the same.

In the accompanying drawings forming 50 part of this specification, Figure 1 is a side-elevation of a cylinder, means for tending to move the cylinder in one direction and means for permitting its movement in that direction, Fig. 2 is a side view of the parts

located at one end of the device shown in 55 Fig. 1, and showing the relative position of the marking devices to the cylinder, Fig. 3 is a detail view of the release device, Fig. 4 is a detail view of the release device mainly in elevation, but partly in section. 60 Fig. 5 shows the relative position of the marking points to the dial when the dial is in its initial position, Fig. 6 is a detail view of the parts as seen from line 6—6 of Fig. 1, showing the same in a position 65 corresponding to the initial position of the dial as shown in Fig. 5, Fig. 7 shows the relative position of the marking points to the dial when the dial is in its second position, Fig. 8 is a detail view of the parts as 70 seen from line 6—6 of Fig. 1, showing the same in a position corresponding to the second position of the dial, Fig. 9 shows the relative position of the marking points to the dial when the dial is in its third position, and Fig. 10 is a detail view of the parts as seen from line 6—6 of Fig. 1, showing the same in a position corresponding to the third position of the dial.

Similar reference characters indicate corresponding parts.

Referring to the drawings, and more particularly to Fig. 1, a cylinder or barrel 21 is provided with a grooved covering 52, over which a dial 51 is placed, adapted to be 85 punctured by the marking points 53, actuated by electromagnets 50, as is well known. On each energization of the electromagnets 50, the armatures are attracted, and these move the marking points against the paper 90 dial. The cylinder 21 is supported by a shaft 28, the ends of which rotate in the standards 22 and 82, being held in position by the collars 24 and 92 one at each side of the standard 82, and secured to the shaft by 95 screws 25. A gear wheel 23, meshing with the usual clock train, is also secured to the shaft, and a cap 26 keeps the gear wheel 23 in position on the shaft. The dial 21 is provided with proper printed markings, 100 transversely and longitudinally arranged corresponding to the number of stations and to the time. The movement of the cylinder 21 is usually so timed as to bring about one complete revolution for each 24 hours, and 105 the magnets, with the marking points actuated thereby, are so arranged longitudinally along the cylinder that on the actuation

of a station, the magnet electrically connected therewith is energized and the dial pricked at that portion immediately in front of it, the marking produced thereby, showing by its relative position, the number of the station and the time when the station was acted upon by the key of the watchman. All this is well known.

In one day clocks dials were used for only 10 one complete rotation, corresponding to one day, and this necessitated the daily renewal of the same by the superintendent or other employee who was given charge thereof. This required his visit to the factory Saturday 15 days and Sundays as well as on other days. In more than one day-clocks, dials are used in which each division, heretofore corresponding only to one station marking, is divided into three parts or subdivisions, one 20 part for each of three days. This division may, if preferable, be divided into seven parts, corresponding to the days of the week. This would require only weekly renewals. In the case shown in the drawings, the dial 25 would not require renewal until after the third day, which is very advantageous not only to cover the period over Sunday but also the period over the holidays.

By the shifting of the cylinder carrying 30 the dial, the several subdivisions are brought into juxtaposition to the marking devices, and for this purpose means are required to effect this shifting. The cylinder is made movable for this purpose in respect to the 35 shaft, and a helical spring 27 is interposed between one end of the cylinder 21 and the collar 24, so as to continually force the cylinder away from the clock-train end of the shaft, or, as shown in Fig. 1, to force the 40 cylinder from the right to the left. To the other end of the shaft 28 is secured a disk 33, having a guide-hole 66 for the passage of a pin 46, supported at the end of the cylinder. On the movement of the cylinder, 45 the pin 46 will move readily in the guide-hole 66. The disk 33 in turn supports a shaft 37 having a nut 38, between which and the disk 33 a release device having a collar 32 is arranged. This collar 32 is provided 50 with an interior flange 67, the innermost end of which abuts against and is adapted to seat and rotate on the disk 33. A portion of the flange 67 is cut away, so as to form a portion 41 and is provided with slots 40, in 55 one of which the end 45 of a spring 44 engages so as to be secured therein, while the other end of the spring is secured to a pin 43, extending from the disk 33. The collar 32 is also provided with an exterior flange 68, the parts of which are cut away, step 60 fashion, so as to form flanges of different heights, corresponding to the number of subdivisions on the dials, or, in other words, to the number of days during which the dial 65 is to be used before removal. The cut-away

portions of steps 69 and 70 are shown clearly in Fig. 3, the flange 68 forming the highest step.

The tendency of the cylinder to be moved sidewise is caused by the action of the spring 70 27, and brings about a pressure of the pin 46 against the seat of the flange 68, as shown in Fig. 1. By rotation of the collar, first the step 68, and then the step 69, is moved away from the pin 46, and thereby, no resistance being offered to the tendency of the cylinder to move in a sidewise direction by the action of the spring on it, a step by step shifting of the cylinder is caused.

The collar 32 is provided on its periphery 80 with pins 34, 35 and 36 extending radially outward and in such a manner as to encounter a stationary pin 31 supported by a vertical extension 29 of the standard 22 on the rotation of the disk 33, and of sufficient 85 length to cause the collar 32 to be positively moved and in a single direction during the continued rotation of the disk 33. A stop pin 42 is secured to the disk 33 and prevents the further rotation of the releasing collar when 90 the shoulder portion 76 abuts against it. The abutting of the other shoulder portion 93 of the flange 39 against the pin 42 limits the movement of the collar and determines its initial position. 95

The operation of my improved device is as follows: With the parts placed in position as shown in Fig. 1 and the collar 32 rotated against the action of the spring 44, the pin 46 of the cylinder pressing against 100 the uppermost seat 68 of the exterior flange of the collar 32, holds the collar against the action of the spring 44, in stationary position. The dial is adjusted in its proper position on the cylinder 21 and the clock-train 105 set in operation.

Fig. 5 shows the corresponding relative positions of marking points 53 of the marking devices to the subdivisions a^1 , a^2 and a^3 of the division A of the dial. The division 110 A would correspond to one station and for one day while the subdivisions a^1 , a^2 and a^3 of the improved dial correspond to the actions of one station during the several days 115 of the three during which my improved dial and device may be used.

The clock train having been set into operation, the cylinder 21 is rotated and arrives near the end of the first 24 hours in such a position as to bring the collar with 120 its extending pins in a position substantially like that in Fig. 6. By the continuing rotation the stationary pin 31 is encountered by the pin 36 of the collar, and the collar rotated thereby on its axis 37. The seat 68 of the exterior flange is moved from under and away from the pin 46 during the time that the pins 31 and 36 are in engagement with each other after which the pin jumps from that seat 68 to the next lower seat or 125 130

step 69. The releasing of the pin 46 from engagement with the seat 68 and into engagement with the seat 69 permits the expansion of the spring 28, and the movement of the cylinder 21 a distance corresponding to the height of the step, from the right to the left, in the embodiment shown in the drawing, causes the "jumping" of the pin just referred to. This shifting movement of the cylinder brings the second subdivision α^2 for instance, in juxtaposition with the marking device and the marking corresponding to the second day is ready to begin. The relative position of the marking device to the dial when in the second position is clearly shown in Fig. 7. The continued rotation of the cylinder brings, at the end of the next 24 hours, the parts in the position shown in Fig. 8, and by the continued rotation, the releasing device is caused to be moved so as to bring about the disengagement of the seat 69 from the pin 46. Simultaneously with the jumping of the pin 46 to the next seat 70, another shifting movement of the cylinder is occasioned. This brings the dial in the position relative to the marking device shown in Fig. 9, or corresponding to the third day, the marking point 53 being in juxtaposition to the subdivision α^3 . The further continued rotation of the cylinder brings the parts at the end of the third day in the position shown in Fig. 10, when the pin 42 will be caused to abut against the shoulder portion 93 of the flange and prevent any further rotation of the collar, and by the next engagement of the pins 31 and 36 on the continued rotation, the rotation of the cylinder and dial is stopped.

The invention therefore consists of a release-device having flanges of different heights and having projections; and also in the combination, of a cylinder tending to move in one direction, and means adapted to be moved positively and in one direction to allow the cylinder to shift in said first named direction at the end of each complete rotation of the same.

By the use of my improved device a dial may be used in electric watchman's clocks which may be placed on the cylinder Friday evenings and, which will take up, until the return of the superintendent to it three days later, all the markings made during the three days.

In the drawings and description, a particular embodiment of my invention has been shown, but it is clear that changes may be made therein without departing from the spirit of the same.

I claim:

1. In an electric watchman's clock, the

combination of a cylinder tending to move in one direction, and automatic means adapted to be moved positively to allow the cylinder to shift in said direction only at the end of each complete rotation of the same. 65

2. In an electric watchman's clock, the combination of a cylinder tending to move longitudinally in one direction, and automatic means normally preventing the movement of the cylinder in that direction and arranged to allow a step-by-step movement of the cylinder in said direction. 70

3. In an electric watchman's clock, the combination of a cylinder tending to move in one direction, and a rotatable release device having flanges of different heights and adapted to successively move at the end of each complete rotation of the cylinder whereby the cylinder is successively permitted to move. 75 80

4. In an electric watchman's clock, the combination of a cylinder tending to move in one direction and having a pin and a release device rotatable with the cylinder and engaged by the pin, said release device being moved successively from under the pin at the end of each complete rotation of the cylinder. 85 90

5. In an electric watchman's clock, the combination of a cylinder tending to move in one direction and having a pin and a spring-actuated release device with flanges of different heights engaged by the pin, said release device being rotatable with the cylinder and having projections adapted to be successively engaged for turning it, thereby permitting the movement of the cylinder. 95

6. In an electric watchman's clock, the combination of a cylinder tending to move in one direction having a collar and a pin, a release device supported by the collar and having flanges of different heights engageable by the pin, said release device having projections, and an abutment successively engaging the projections of the release device for turning it, thereby permitting the movement of the cylinder. 100 105

7. In an electric watchman's clock, the combination of a cylinder tending to move longitudinally in one direction, and a movable release device positively coöperating with the cylinder and having a cam adapted to permit the cylinder to move in said direction. 110 115

In testimony, that I claim the foregoing as my invention, I have signed my name in presence of two subscribing witnesses.

GEO. B. FESSENDEN.
